UNITED STATES PATENT OFFICE.

SAMUEL F. GREENE, OF YONKERS, NEW YORK.

MONOTYPE CASTING-MACHINE.

1,097,714.

Specification of Letters Patent.

Patented May 26, 1914.

Application filed October 26, 1910. Serial No. 589,098.

To all whom it may concern:

Be it known that I, SAMUEL F. GREENE, a citizen of the United States, and a resident of the city of Yonkers, county of West-
5 chester, and State of New York, have in-
vented certain new and useful Improvements in Monotype Casting-Machines, of
which the following is a full, clear, and
exact specification.

10 The object of my invention is the devising of mechanism which, when combined with certain existing mechanisms of the mono-
type casting machine will operate to stop the type casting process without otherwise af-
15 fecting the operations of the machine, until
at such time as it may be desired to again proceed with the casting of type.

20 A further object of my invention is to devise means adapted to be operated to cut
20 out the type casting process during a pre-
determined period, which may be regulated
by the operator at the keyboard.

25 The machine as at present known is capable
of cutting out the casting operation for
a definite time during a specific period, pre-
arranged by the operator at the keyboard.
That is to say, a single piece of type is ordi-
narily cast at each revolution of the belt
30 wheel of the machine, but the operator may
if he desires so perforate the ribbon, that
during a predetermined revolution of the belt
wheel the casting operation will be sus-
pended and replaced by a different cycle
35 of movements. This, however, will only last
during one revolution of the belt wheel, or
during the time required for casting a single
type, unless the operator repeat the perfor-
ation on the ribbon at the keyboard. The
40 machine is also provided with hand operated
mechanism for cutting out the casting pro-
cess. Either method of suspending the casting
is ultimately accomplished by discon-
necting the mechanism operating the pump,
45 used to force metal into the mold. In my
invention I also prefer to make use of this
same pump disconnecting mechanism. But
I claim broadly any means to be used in
conjunction with and operated by suitable
50 mechanisms of the monotype casting ma-
chine, to the end that the operator at the
keyboard may at pleasure effect a cutting
out of the casting process for any period of
time, at any point in the preparation of his
55 ribbon by simply striking the proper keys
at each end of the space on the ribbon which
corresponds to the period he desires to dis-

continue the casting operation. I therefore
do not limit myself in an application of my
invention to the pump disconnecting mech-
anism alone, for I well know the above re-
50 sults can be attained by any means that will
prevent the metal from getting into the
mold; as for instance, if the nozzle of the
pump be kept away from the orifice in the
mold, even though the pump be continually
55 operated, or, if the mold orifice be closed
by any means to prevent metal from enter-
ing it and such mechanisms could be oper-
ated by use of the same perforations in the
ribbon as are employed in my preferred em-
60 bodiment as shown in the drawings.

65 My invention is most useful, as far as I
am at present aware, for the purpose of
killing a line. This is necessary when the
operator has made an error as by striking a
70 wrong key, and thus made a wrong perfora-
tion in the ribbon (which cannot be recti-
fied). The line in which the error appears
cannot be used in printing. It is obvious
75 therefore that such a line should not be cast,
80 and my invention is devised to hold the
casting process in check while that portion
of the ribbon representing the line contain-
ing the error is being fed to the caster.

85 It must be remembered that the keyboard
contains 225 keys, each one operating to cast
but a single piece of type, and many of such
pieces being necessary to make a line. It
can easily be seen, therefore, that in choos-
ing the proper key each time from a group
90 of 225, it is very likely that before so many
keys are struck as will make a line on the
galley, a mistake may often happen by
pressing a wrong key. As can easily be
95 seen, these mistakes are of frequent occur-
rence, and it is the object of my invention
to prevent them from affecting the output
of the machine as far as possible.

100 The old way of treating a line (killing a
line) in which an error had been made, was
for the operator, as soon as he discovered
the error, to repeatedly strike the quad key
(or sometimes the w key on account of its
105 size), and thus complete the line as quickly
as possible. He then started a new line in
the usual way, beginning with the matter
that was on the line that was killed. The
operator at the casting machine then had
110 to inspect the galley and to withdraw there-
from whatever lines contained mistakes.
This method caused a loss of time, both at
the casting machine and keyboard, and as

the entire line was cast, it was also an unnecessary wear and tear on the machine and a loss in time during the casting of the line.

Another method of killing the line is by 5 the operator stopping his work when he finds he has made a mistake, to roll back the perforated ribbon to the beginning of the line in which the mistake occurs, and then to repeatedly strike a justification key 10 until he arrives at the mistake, or at the point where he first discovered it. He then restores and resets the line in the usual way. When this part of the ribbon is presented to the caster, it will repeatedly throw the 15 pump out of casting operation, for each revolution of the belt wheel, (or perforation in the line) until the killed line (or portion of the line) is fed past the caster. This method leaves nothing for the operator at 20 the casting machine to do in regard to the killed line, for there is no type cast. There is, however, wear and tear on those parts thrown into operation, on account of continually striking the justification key. There 25 is also loss of time at the keyboard, while repeatedly striking the justification key.

By the use of my invention all that need be done to kill a line is for the operator to strike one of the lower justification keys. 30 He then restores and resets the line. When this line (or portion of line) containing the error is passing the caster, the casting process is stopped once for all until the killed line has been passed by. The operator at 35 the casting machine need pay no attention to the matter whatever, as there is no type cast, and there is no wear or tear as previously remarked.

Referring now to the drawings which 40 illustrate my invention in conjunction with suitable parts of the monotype casting machine, Figure 1 is a front elevational view partly in section of my invention, combined with parts of the monotype casting machine, 45 also partly shown in section. Fig. 2 is an end view of the lower right hand part of Fig. 1, Fig. 3 is a view of the parts shown in the lower left hand corner of Fig. 1, and at right angles thereto, and Figs. 4, 5 and 50 6 are fragmental plan views partly in section showing three positions of the operating mechanism shown in Fig. 1.

The mechanism I devise is shown in the parts of the drawings indicated by the reference letters A, B, C and D. The other parts shown in the drawings are those belonging to the monotype casting machine.

The ribbon of the casting machine is prepared at the keyboard by the operator by 60 compressing keys much as in ordinary type-writing, which perforates the paper ribbon with a succession of holes running with the paper. Their positions across the paper depend upon the keys struck. This roll determines the matter to be printed. It is

presented to the casting machine and each perforation (with a few exceptions soon to be explained) determines a specific type to be cast. Ordinarily only one perforation is presented to the casting machine during one 70 revolution of the belt wheel.

It is not necessary for the purpose of my invention to give a detailed description, or in fact any description at all, of most of this complex machine. Some parts, however, must be more fully explained.

The machine is driven by a shaft, driven by a belt wheel. The ribbon, by the predetermined positioning of its perforations, is responsible for the extent to which certain parts of the machine move. That is to say, it determines their stopping places. It also cuts in or out certain other parts to give them motion or no motion all in a predetermined manner, with the ultimate result that each piece of type is cast separately, formed into a line, properly justified, and then placed on the galley ready for the press. The operator after completing his line by striking the proper type keys and space key 90 has still to justify the line before beginning a new one. The upper two rows of keys on the keyboard, are the justification keys. These are operated to justify the line after it is otherwise completed by the operator. 95 The mechanism affected by perforations formed by these keys have most to do with my invention and will require to be clearly understood.

The mold in which the body of the type is 100 cast has among other things (unnecessary to describe here), a rear wall that may be adjusted in or out, called the blade. This blade is reset for each revolution of the belt wheel to determine the correct width of the type 105 body for the particular type cast at that revolution. Each position of the blade is dependent on the specific perforation in the ribbon at that time presented to the caster. The molten metal is forced into the mold 110 from the bottom thereof by means of a pump. The positioning of the blade is effected by a wedge called the normal wedge, sliding transversely to the blade and acting through an intermediary as a backing or 115 stop for the blade, changing its position and the width of the type cast as the wedge moves to and fro. Each type represented on the ribbon, by a specifically positioned perforation, sets this wedge in a specific position. As each line may require a different thickness of spacing other means are adopted which in conjunction with the spacing key when depressed will set the normal wedge so that the proper thickness of space 120 will be cast to justify the line. To accomplish this, the normal wedge is made high enough to accommodate at its back two wedges, placed one upon the other, the lower one being called the type transfer wedge, 130

the upper one the space transfer wedge. The lower one is the backing for the normal wedge when type is cast and is itself backed up by an abutment. The upper one is the 5 backing for the normal wedge when a space is cast.

Mechanism is provided so that the spacing key will effect a locking of the lower wedge (type transfer wedge) out of engagement 10 with the normal wedge and will at the same time throw the upper wedge (space transfer wedge) in, as a backing for the normal wedge. This upper wedge is provided with a backing of two other wedges, placed one 15 behind the other, called the justification wedges. It is the proper setting of these wedges that determines the thickness of the space cast to justify the line. The wedges termed the type transfer wedge and space 20 transfer wedge are strictly speaking, only backings for the normal wedges and have no automatic adjustment except to be thrown in and out of engagement as above described. The upper one is thrown in, 25 through the instrumentality of the space key and after the space is cast the wedge is automatically thrown out and the lower wedge thrown in for type casting.

The justification wedges are set by means 30 of the justification keys. The upper row effects a setting of the front justification wedge and the lower row the back wedge. The operator when he has finished a line strikes the proper justification keys as indicated by the scale pointer.

It requires a revolution of the belt wheel to set a justification wedge, and during such a revolution the casting pump must be inoperative. Therefore, the controlling means 40 for setting the wedges is employed to cut out the pump. The ribbon roll is fed to the caster in the reverse order to its travel at the keyboard; that is to say, the last line is cast first, and it is likewise the last perforation in 45 each line that is first presented to the caster. It is therefore the justification wedges that are first set before the line is cast. The mechanism that is employed to set the wedges, besides cutting out the pump while 50 the wedges are being set, also effects a removal of the line of type from the caster to the galley. It is these several parts now under consideration that are made use of by me in connection with my means for permanently locking out the pump until the killed 55 line had passed beyond the caster. As before stated, in my invention, to kill a line the operator has only to strike one of the lower justification keys and to then restore 60 and reset the line. Without my device the perforation made by this key would effect a cutting out of the pump for the one revolution, but with my invention the pump is locked out of operation permanently; that 65 is to say, until my locking mechanism is re-

leased. The releasing is accomplished through striking a justifying key from the upper row. The ribbon, as just stated, operates in a reverse order from which it is formed, the lower justification key that was 70 struck to kill the line is therefore first to meet the caster. The pump is permanently stopped and then each perforation in the ribbon passes over the caster, one for each revolution of the belt wheel, putting the machine through all its operations at each 75 revolution but without casting any type (as the pump is locked) until the justification perforations belonging to the line set by the operator previous to the killed line meet 80 the caster. One at least of these perforations was struck from the upper row at the keyboard, and when this reaches the caster, my locking device is released, and the pump is again operative. It will then be seen that 85 a perforation from a lower justification key will kill the line by locking out the pump, for the next perforation to be presented. On this account, as the keys used to justify the previous line are relied upon to release 90 my device, and as a lower key will lock it, it must always be remembered in justifying that the operator first strikes an upper key, whether it be single or double justification. This will present a perforation made by an 95 upper key to the caster just previous to beginning to cast the live line and will insure a releasing of the pump in time to cast the first type in this line.

Referring to the drawings, the front justification wedge 1 is shown in cross-section. It is provided with teeth 2 along its bottom. These engage with a permanent tooth (not shown) to lock the wedge in any set position. To reset the wedge, it must first be 100 raised free from the stationary tooth. This raising engages it with mechanism, the extent of whose motion is dependent upon the particular perforation then passing the 105 caster made by striking the desired justification key. The wedge again drops and is locked by the before mentioned tooth. The other wedge and mechanism is similar to the one just described. The wedge shown, however, is the front wedge and is operated by 110 means of the upper row of justification keys and its raising mechanism is used to release my locking mechanism as before stated, while the raising mechanism of the other wedge acts to lock the pump. Part of the 115 mechanism for raising the wedge 1 is shown. It comprises a lever 3 fulcrumed on the pin 4 permanently secured in the machine. The lever has an upwardly extending arm 5 pivoted to it by pin 6. The upper part of the 120 arm is reduced to a rod 7. The upper end of the rod is provided with an adjustable head (not shown) and is adapted to fit in the crotched end of an upwardly and downwardly moving lever called the centering 125 130

pin lever (not shown). This up and down motion of the arm 5 swings the lever 3 and effects a raising and lowering of the wedge through its contact therewith at the point 3'. The rod 7, however, when in normal position is out of engagement with the crotch, as it is normally pulled to the right, and away from the crotch by a tension spring (not shown) hooked to the hook 8 formed on the extension 9. When, therefore, one of the perforations, formed by striking a key in the upper row of justification keys is presented to the caster, an air pin is blown up which strikes the horizontal leg of the bell crank lever to raise it, and to force the vertical leg 10 forward. This forces the rod 7 into engagement with the crotch, which rises and falls once for each revolution of the belt wheel. When the rod 7 lowers with the crotch, it springs out of engagement therewith as just described. It will thus be seen that the lever 3 can only be swung once for each revolution of the belt wheel.

The back justification wedge (not shown) is operated by similar mechanism as the one shown. It has similar operating mechanism as wedge 1 and need not therefore be particularly described. The lever 3 has the downwardly extending arm 11 provided with a nose 12. Figs. 4, 5 and 6 show the downwardly extending arm 11' and nose 12' forming part of the raising lever for the above referred to justification wedge not shown. Below the lever is a rod 13 slidably mounted in bearings 14 formed in the frame of the machine. On the front end of this rod is rigidly secured a downwardly and rearwardly extending arm 15. On the top of the arm is pivoted in horizontal position a rocker 16 by pin 17 and adapted to rock in a horizontal plane. As clearly shown in Figs. 4, 5 and 6 when either wedge-raising lever is swung to raise its wedge, its nose is swung in also. Fig. 5 shows the nose 12' and Fig. 6 the nose 12 as carried in. In either case of the swinging in of the nose, the rod 13 and arm 15 secured to the center of the rocker will likewise be carried in (to the left). The end of the rod 13 operates to set the mechanism necessary to place the line of type just cast upon the galley. Below the rod is the mechanism for engaging the pump with its driving mechanism. The pump is driven through the medium of a bell crank and a cam lever, motion being transmitted from the cam lever to bell crank through a connecting rod 18. The rod 18 is broken at a convenient place and the ends are connected by the mechanism shown in Fig. 3 and the left hand lower corner of Fig. 1. The break in the connecting rod 18 on the cam lever side has on its end the fork 19. In this fork is pinned the link 20 by pin 21. The other end of the link 20 by pin 23. The two links are pinned together at their lower ends by pin 24. The links are free to swing on the pins 21, 23 and 24. Therefore as the cam lever 70 end of the connecting rod 18 is moved to and fro it will effect no motion of the other end; that is to say, the bell crank end of the connecting rod and therefore the pump will not be operated. To lock the two ends of the connecting rod together the following mechanism is provided. On the pin 23 is loosely mounted latch 25. The latch has a lip 26 adapted to engage with the link 20 when its upper end and that of link 22 are 80 brought together as shown dotted in Fig. 3, and thus to lock the two ends of the connecting rod together. The motion of the cam lever will thus be imparted to the bell crank to effect a driving of the pump. 85

The pivoted end of the latch is provided with an extension 27 which coacts with a collar 28 when brought in proper position to effect an unlatching of the parts and thus disconnect the pump. The collar 28 is secured on a rod or tube 29 mounted to slide in bearings 30, formed in the frame. On the end of this rod is loosely pinned an upwardly extending lever 31 called the trip lever. This lever is pinned at its upper end 90 to lug 32 formed on the frame. The trip lever is provided with a pin 33 which engages a shoulder 34 formed in the end of the arm 15. The lever 31 is thus always swung in by the arm 15 as it is pushed by 100 either one of the nose pieces 12 or 12'. The moving of the rod 29 to the left brings the collar 28 into engagement with the extension 27 to raise the latch and disconnect the pump. This only acts for one revolution of the belt wheel, for immediately when the pressure of the arm 15 is released, (that is to say, when the noses are back in their normal positions), the rod 29 comes back to its normal position due to the pull exerted by 105 the tension spring 35 secured to the frame at one end (not shown) and at its other end to the rod 29 by means of pin 36. The collar 28 is thus freed from engagement with the latch 25 and as soon as the arm 20 110 moves back to contact with the arm 22, the lip 26 of the latch, which has been riding on the top of arm 20 now drops down behind it and once more locks the pump in 115 working position. 120

My invention is devised to hold the rod 29 in (to the left), so that the latch 25 will be continually raised until at such time as it is desired to again set the pump in operation. To accomplish this I provide a locking lever 125 B. This lever has one end pivoted to the rod 29, or for convenience of installation to the foot of the arm 31 by means of screw a. A locking plate D is secured by screws b to the frame of the machine, at the back there- 130

- of, positioning the upper part opposite an orifice in the back of the frame intended for inspection of the working parts. In the locking plate D is a vertical slot *c* through 5 which projects the free end of the locking lever B. The locking lever fits loosely within the slot and sets on the bottom thereof to freely slide to and fro with the movement of the rod 29. A shoulder *d* is formed 10 in the lever to permit it to drop when the rod 29 is in its extreme position to the left, bringing the shoulder *d* to coact with the back of the plate D, as shown in Fig. 1. The pump in this position is locked from 15 operation. The end of the lever B is preferably formed into a handle B'. This affords a hand operated means for setting or releasing the locking lever should the operator of the casting machine so desire.
- 20 To release my locking lever to permit the pump to again operate, I provide the following means: Above the locking lever I provide a lifting lever A. This lever is fulcrumed on the arm 31, by means of screw 25 *e*. Its forward end is connected to the locking lever B by means of link C. Its other end is turned upward and forward forming a nose *f* positioned to coact with the end of the rocker 16 opposite the nose 12. This 30 end of the rocker, when it moves inwardly, pushes the nose *f* with it, raising the front end of the lifting lever A, which brings with it the locking lever B. The spring 35 is free to act when the locking lever is 35 raised sufficiently to permit the shoulder *d* to clear the bottom of the slot *c*, and restores the pump into working operation.
- The parts of my device are so proportioned that the bar 29 will move to the left 40 sufficiently when the arm 15 pushes it in that direction to lock the locking lever B and when the forward end of the rocker swings back (that is to the left) the locking lever will be raised sufficiently to release it from the plate D.
- Reconsidering the various operations effecting my invention they are briefly as follows:—The operator justifies his line, always taking care (whether it be single or 50 double justification) that he first strike one of the keys in the upper row of justification keys. After he has justified the line, he then restores his machine and starts a new line. This let us suppose he wishes to kill. 55 To do this he strikes a single justification key of the lower row, restores his machine and resets the line. In being presented to the caster, the perforated ribbon acts in the reverse order to which it was prepared.
- 60 Therefore, considering the killed line, the perforation made by the justification key of the lower row is first presented to the caster. This swings the nose 12' and end of the rocker 16 adjacent thereto in, which forces 65 to the left rod 18, arm 15, lever 31, rod 29 and locking lever B. The shoulder *d* drops into locked position. The locking lever B and pump releasing mechanism is thus fixed, and the pump disconnected. The other parts return to their normal positions. 70
- With the pump locked out of operation, the other parts continue to make their usual cycles of motions as each perforation of the killed line is presented to the caster, until the last perforation has passed and the justification perforations are presented. These 75 set the justification wedges and the last one presented must be one from the upper row of justification keys. This operates an air pin to force the leg 10 of the bell crank 80 against arm 5 forcing rod 7 into the crotch of the centering pin lever (not shown). This raises arm 5, swings lever 3 (raises wedge 1) carrying arm 11 to the left. This 85 swings the adjacent end of rocker 16 to the left, which coacts with nose *f* forcing it to the left, to swing the lifting lever A about its fulcrum *e* to effect a raising of the locking lever B. The spring 35 is then free to act and it draws the collar 28 to the right 90 and away from the latch 25. This latch then drops down as before described bringing the pump again into casting operation ready to cast the first type represented by the next 95 perforation as it is presented to the caster.
- I have preferred to use one of the keys from the lower row of justification keys to effect a setting of my locking lever in locked position and to use a key from the upper row to release the lever, but I do not deem it beyond the scope of my invention if the order be reversed and the movements and mechanisms are so arranged that the upper row of 100 justification keys will set the locking lever and the lower row of keys will release it. 105 The manner of the justification and the proximity of the several parts which I use in conjunction with my device, make it preferable that I use the justification keys in the order described. 110
- Having thus described my invention, I claim:
1. A control mechanism for pattern governed type casting machines including, in combination, the following elements, to-wit; 115 independent signal controlled designating members; pump arresting means; and transmitting devices provided with locking means for retaining the pump arresting devices in the operative position consequent upon the 120 movement of one only of said designating members.
  2. A control mechanism for type-casting machines including, in combination, the following elements, to-wit; independent signal controlled designating members; pump arresting devices; and intermediate transmitting devices including a locking means responsive to one of said designating members. 125
  3. A control mechanism for type-cast- 130

- ing machines including, in combination, the following elements, to-wit; independent signal-controlled designating members; pump arresting devices; and intermediate transmitting devices including a locking means responsive to one of said designating members and releasing means responsive to the other of said designating members.
4. A control mechanism for type-casting machines including, in combination, the following elements, to-wit; independent signal-controlled designating members; automatically returnable pump arresting devices operatively responsive to said designating members; and control mechanism for said pump arresting devices including a locking means responsive to one of said designating members.
5. A control mechanism for type-casting machines including, in combination, the following elements, to-wit; independent signal-controlled designating members; automatically returnable pump arresting devices operatively responsive to said designating members; and control mechanism for said pump arresting devices including a locking means responsive to one of said designating members.
6. A control mechanism for type-casting machines including in combination, the following elements, to-wit; independent signal-controlled designating members; automatically returnable pump arresting devices operatively responsive to said designating members; and control mechanism for said pump arresting devices including a locking lever responsive to one of said designating members and releasing means responsive to the other of said designating members.
7. A control mechanism for type-casting machines, including, in combination, the following elements, to-wit; independent signal-controlled designating members; automatically returnable pump arresting devices operatively responsive to said designating members; and control mechanism for said pump arresting devices including a locking lever responsive to one of said designating members, and a releasing lever responsive to the other of said designating members.
8. A control mechanism for type-casting machines including, in combination, the following elements to-wit; independent signal-controlled designating members; automatically returnable pump arresting devices operatively responsive to said designating members; and control mechanism for said pump arresting devices including means lockably responsive to one of said designating members, and releasably responsive to the other of said designating members.
9. A control mechanism for type-casting machines including, in combination, the following elements, to-wit; independent signal-controlled designating members; automatically returnable pump arresting devices operatively responsive to said designating members; and control mechanism for said pump arresting devices including a locking lever responsive to one of said designating members operating between a fixed part of the machine frame and a part of the said pump arresting devices in pivotal connection at one end with one of said parts, locking means at the other end of said lever, and means for releasing said lever responsive to the other of said designating members.
10. A control mechanism for type-casting machines including, in combination, the following elements, to-wit; independent signal-controlled designating members; automatically returnable pump arresting devices operatively responsive to said designating members; and control mechanism for said pump arresting devices including a locking lever responsive to one of said designating members, pivoted to said pump arresting devices at one end, means at the other end for locking said lever, a second lever above said first lever responsive to the other of said designating members also pivoted to said pump arresting devices, and a link connecting the said levers at their free ends to effect a releasing of the first lever by the operation of the second lever.
11. A control mechanism for type-casting machines including, in combination, the following elements, to-wit; independent signal-controlled designating members; automatically returnable pump arresting devices operatively responsive to said designating members; and control mechanism for said pump arresting devices including a locking lever responsive to one of said designating members pivoted to said pump arresting devices at one end and having a niche at the other end, a slotted plate secured to the machine frame to slidably receive the said niched end to lock the said lever, a second lever above said first lever also pivoted to said pump arresting devices, a link connecting the said levers at their free ends, said second lever having its opposite end hook-shaped to make it responsive to the other of said designating members to release said first lever.
12. In a type-casting machine, a pair of independent signal-controlled designating members, automatically returnable pump arresting devices operatively responsive to either of said designating members, a swinging arm pivotally connected at one end to the frame of said machine and at the other end to the said pump arresting devices and a control for locking and unlocking said pump arresting devices adapted to be pivotally secured to said swinging arm in manner to be responsive to the said two designating members.

bers respectively to lock and unlock the said pump arresting devices, comprising the members A, B, C and D for the purposes as set forth.

5 13. In a type-casting machine having pump driving mechanism including a latch for making effectual said mechanism and means for releasing said latch; means for holding said releasing means in engagement 10 with the said latch for a predetermined period, and other means to release the said holding means.

14. In a type casting machine having pump driving mechanism including a latch 15 for making effectual said mechanism and means for releasing said latch; means for holding said releasing means in engagement with the said latch for a predetermined period, means operating said holding means 20 at a predetermined time in the working of said machine, other means operable to discontinue the operation of the said holding means, and other means operating said discontinuing means at a predetermined time 25 in the working of said machine.

15. In combination a pump trip tube, means for moving said tube forwardly, means for automatically restoring said tube, means for holding said tube against return 30 movement, said last named means arranged to be automatically actuated, and means for throwing said holding means out of operation.

16. In a type-casting machine as described, pump arresting devices, a latch 25 adapted to be raised for making effective said arresting devices, a collar 28 to engage the said latch to hold it in said raised position, a locking lever to retain the said collar 28 in engagement with the said latch 25, and means for releasing the said locking lever.

17. In a type-casting machine having pump driving mechanism including a latch 45 for making effectual said mechanism and automatically returnable means for releasing said latch; a locking lever having one end free to be raised and lowered, means for locking said end in one of said raised 50 or lowered positions to operate said latch releasing means for a predetermined time, and other means for releasing said locked end.

18. In a casting machine having a pair 55 of independent justification wedge-raising means and pump driving mechanism including a latch for making effectual said mechanism and an automatically returnable slid- 60 able bar for releasing said latch each of said wedge-raising means being adapted to effect a moving of the said slidable bar to release the said latch; means for automatically locking said slidable bar when moved by one of said wedge-raising means, and means 65 for releasing the said locking means oper-

ated by the other of said wedge-raising means.

19. In a casting machine having a pair of independent justification wedge-raising means and pump driving mechanism includ- 70 ing a latch for making effectual said mechanism, an automatically returnable slidable bar, and a collar on said bar for releasing said latch, each of said wedge-raising means being adapted to effect a moving of the said slidable bar to release the said latch; a locking lever having one of its ends free, means at said free end to automatically lock said lever when said slidable bar is moved by one of said wedge-raising means, and other 75 means for unlocking said lever operated by the other of said wedge-raising means.

20. In a casting machine having a pair of independent justification wedge-raising levers and pump driving mechanism including 80 a latch for making effectual said mechanism, an automatically returnable slidable bar, an extension from said bar for releasing said latch when said bar is moved in one direction, a swinging arm pivoted at one end to 85 the frame of the casting machine and at the other end to the slidable bar, and means operated by either of said wedge-raising levers for swinging said arm to slide said bar to release said latch; mechanism operated to 90 permanently release said latch comprising a locking lever carried by said swinging arm, means for locking said lever when moved with said slidable bar by one of said wedge-raising levers to permanently release 95 said latch, and other means operated by the other of said wedge-raising levers to unlock 100 said locked lever.

21. In a casting machine having a pair of independent justification wedge-raising 105 levers and pump driving mechanism includ- 110 ing a latch, an automatically returnable slidable bar, an extension from said bar for releasing said latch when the said bar is moved in one direction, a swinging arm pivoted at one end to the frame of the casting machine and at the other end to the slidable bar, and means operated by either of the said wedge-raising levers for swinging said arm to slide said bar to release said latch; mech- 115 anism for permanently releasing the said latch comprising a lever carried by said swinging arm, means for locking said lever when moved with said slidable bar by one of said wedge-raising levers to release said 120 latch, a second lever pivoted to said swinging arm above the said first lever, and a link connecting the two levers together at their free ends, the said second lever having its opposite end formed to be moved by the 125 other of said independent wedge-raising levers to effect a raising of the free ends of the linked levers to unlock the said lower lever.

22. In a casting machine having a pair 130

of independent justification wedge-raising levers and pump driving mechanism including a latch, an automatically returnable slideable bar, an extension from said bar for releasing said latch when the said bar is moved in one direction, a swinging arm pivoted at one end to the frame of the casting machine and at the other end to the slideable bar, and means operated by either of the said wedge-raising levers for swinging said arm to slide said bar to release said latch; mechanism for permanently releasing the said latch comprising a lever pivoted at one end to said swinging arm to be carried thereby and having a niche formed in its opposite end, a plate rigidly secured to the machine frame having a slot for retaining the said niched end of said lever in sliding

contact therewith and for engaging the said niche to lock the said lever when the said slideable bar is moved to release the said latch by one of said wedge-raising levers, a second lever pivoted to said swinging arm above the said first lever, and a link connecting the two levers together at their free ends, the said second lever having its opposite end formed to be moved by the other of said wedge-raising levers to effect a raising of the free ends of the linked levers to unlock the said lower lever.

In witness whereof I have hereunto set my hand in the presence of two witnesses.

SAMUEL F. GREENE.
